Primary Examiner — Jennifer L Rempfer(74) *Attorney, Agent, or Firm* — Sean R. Wilsusen, Esq.;
Carter, DeLuca & Farrell LLP(57) **CLAIM**

The ornamental design for a pillow with device pocket, as shown and described.

DESCRIPTION

FIG. 1 is top perspective view of a pillow with device pocket;

FIG. 2 is a bottom perspective view thereof;

FIG. 3 is a top plan view thereof;

FIG. 4 is a bottom plan view thereof;

FIG. 5 is a first side view thereof;

FIG. 6 is a second side view thereof; and,

FIG. 7 is a third side view thereof.

The broken lines in the drawings representing a smartphone and a charging cord form no part of the claimed design. The broken lines surrounding the device pocket represent stitching and form part of the claimed design.
